(57) **CLAIM**

The ornamental design for a compliant ground block and testing system for testing integrated circuits, as shown and described.

DESCRIPTION

FIG. 1 is a Top Perspective view of a compliant ground block and testing system for testing integrated circuits showing the new design;

FIG. 2 is a Bottom Perspective view thereof;

FIG. 3 is a Front view thereof;

FIG. 4 is a Back view thereof;

FIG. 5 is a Left view thereof;

FIG. 6 is a Right view thereof;

FIG. 7 is a Top view thereof; and,

FIG. 8 is a Bottom view thereof.
